UNITED STATES PATENT OFFICE.

JAMES THOMAS HAM, OF MONAHANS, TEXAS.

WINDMILL.

SPECIFICATION forming part of Letters Patent No. 738,675, dated September 8, 1903.

Application filed February 18, 1903. Serial No. 143,914. (No model.)

To all whom it may concern:

Be it known that I, JAMES THOMAS HAM, a citizen of the United States, residing at Monahans, in the county of Ward and State 5 of Texas, have invented new and useful Improvements in Windmills, of which the following is a specification.

My invention relates to new and useful improvements in windmills; and its object is to 10 provide a device of this character having a wheel of novel construction whereby the wind coming into contact therewith is concentrated and the full force thereof applied to the wheel.

A further object is to employ means whereby motion is imparted from the wheel to apparatus located adjacent thereto.

Another object is to provide a balance for the mechanism whereby the power necessary to operate it is reduced to the minimum.

With the above and other objects in view the invention consists in the novel construction and combination of parts hereinafter more fully described and claimed, and illustrated in the accompanying drawings, showing 25 the preferred form of my invention, and in which—

Figure 1 is a front elevation of my improved windmill. Fig. 2 is a side elevation thereof with the supporting-frame in section. Fig. 3 30 is a section on line $x-x$, Fig. 1. Fig. 4 is a section on line $y-y$, Fig. 1; and Fig. 5 is a section through the wind-wheel.

Referring to the figures by numerals of reference, 1 is a supporting-frame of suitable 35 height, and a preferably rectangular head 2 is arranged therein and bears upon a cross-beam 3, as shown. A stem 4 extends upward from the center of the head 2 and bears within the top of frame 1, and hinged to this stem

40 are a tail-vane 5 and a side vane 6. An arm 7 projects from stem 4 in alinement with the side vane and is connected by a rod 8 with the arm 9 of tail-vane 5. A spring 10 serves to hold the vane 5 normally in proper relation 45 to the wheel. This wheel comprises a cylindrical casing 11, supported upon a shaft 12 by arms 13. This shaft is journaled in the sides of the head 2 and has a crank 14 at each end thereof. Curved blades 15 are interposed 50 between the shaft 12 and casing 11.

A cross-head 16 is slidably mounted in slots 17, formed in the sides of head 2, and the

ends of the cross-head are connected to the cranks 14 by pitmen 18. To the center of the cross-head is swiveled a pump-rod 19, which extends down through the lower bearing of the head 2 and has a saw-blade 20 connected thereto and adapted to reciprocate therewith. A shaft 21 is journaled near the rod at the bottom, and at each end thereof 60 is arranged a toothed wheel 22, and these extend to opposite sides of the blade 20. Inclined stationary cutting-blades 23 are mounted on the bottom of frame 1, and a lever 24 is fulcrumed thereto and has its two edges 65 sharpened to form a knife 25. One end of the lever is connected to the rod 19 by a link, while the other end has an adjustable weight 26 thereon.

Wind upon coming into contact with the 70 blades 15 is prevented from flowing laterally therefrom by the cylindrical casing 11. This casing holds or concentrates the wind, and the full force thereof is therefore imparted to the wheel. As the wheel revolves a reciprocating 75 movement is imparted to rod 19 by the cranks 14 and pitmen 18, and saw-blade 20 and lever 24 are moved therewith. By placing a log on the wheels 22 the weight thereof will cause them to revolve, and it will be fed to the saw. 80 The weight 26 can be adjusted upon lever 24, so as to act as a counterbalance, and straw or other similar material can be placed between either blade 23 and the knife 25 and will be quickly cut thereby.

A pulley 27 may, if desired, be arranged on shaft 12, and a belt 28 thereon will transmit motion to a pulley 29, mounted at a desired point in the head 2. The power obtained in this manner may be employed for driving a 90 mill or for any other desired purpose.

In the foregoing description I have shown the preferred form of my invention; but I do not limit myself thereto, as I am aware that modifications may be made therein without departing from the spirit or sacrificing the advantages thereof, and I therefore reserve 95 the right to make such changes as fairly fall within the scope of my invention.

Having thus described the invention, what 100 is claimed as new is—

1. In a windmill, the combination with a frame, a rotary head mounted therein, and a wheel journaled in the head; of a cross-head

- slidably mounted in the head, means for imparting motion thereto from the wheel, a pump-rod connected to the cross-head, a cutting-lever fulcrumed in the frame, a link connection between the lever and rod, and an adjustable weight upon the lever.
2. The combination with a frame, a rotary head therein, a crank-shaft in the head and a wheel secured to the shaft; of a cross-head 10 slidably mounted in said head, a pitman connecting said cross-head and the crank-shaft, a pump-rod secured to the cross-head, cutting-blades, a cutting-lever fulcrumed therebetween, a link connecting the lever and rod, 15 and an adjustable weight upon the lever.
3. The combination with a frame, a rotary head therein, a crank-shaft in the head and a wind-wheel secured to the shaft; of a cross-head slidably mounted in the head, a pitman 20 connecting said cross-head and the crank-shaft, a pump-rod connected to the cross-head, a saw-blade secured to and projecting from said rod, a lever connected to the rod, and an adjustable weight upon the lever.
4. The combination with a wind-wheel, a 25 rod, and means for transmitting motion from the wheel to the rod; of a cutting-lever connected to and operated by the lever, an adjustable weight upon said lever, a knife adjacent to the lever, and a saw-blade upon the 30 rod.
5. In a windmill, the combination with a frame; of a head revolvably mounted therein, vanes hinged to the head, a crank-shaft journaled in the head, a wheel thereon, a cross- 35 head slidably mounted in the head, a pitman connecting the shaft and cross-head, a rod extending from the cross-head, a saw-blade thereon, a cutting-lever connected to the rod, and an adjustable counterbalance-weight 40 upon the lever.

In testimony whereof I affix my signature in presence of two witnesses.

JAMES THOMAS HAM.
